UNITED STATES PATENT OFFICE.

JOHN M. MARTY, OF CLARKSVILLE, ARKANSAS.

COMBINED INJECTOR AND EJECTOR.

SPECIFICATION forming part of Letters Patent No. 314,595, dated March 31, 1885.

Application filed July 14, 1884. (Model.)

To all whom it may concern:

Be it known that I, JOHN M. MARTY, a citizen of the United States, residing at Clarksville, in the county of Johnson and State of Arkansas, have invented certain new and useful Improvements in Combined Injector and Ejector; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to improvements in combined injectors and ejectors, as herein-after fully described and set forth.

Figure 1 is an inside face view of the lower half, B, of the body of my double combined injector and ejector, and longitudinal views of the tubes *a*, *b*, *c*, *d*, and *e*, regulating-plug *f*, steam-head plugs *g* *g'*, bushings *h* *h'*, packing-glands *j* *j'* and *k*, gasket-sockets *j'* *j''* and *k'*, check-valve *l*, and levers *M*. Fig. 2 is an edge 25 view of my injector, showing its upper and lower halves, A and B, its studs *n* *n'*, packing-glands *j* *j'* and *k*, self-stopping overflows *o* and *p*, *o* being a sectional view showing the head *p'*, pin *p''*, and stopper *p'''*. Fig. 3 is a detail 30 sectional view of packing-gland *k*, and a view of the regulating-plug *f*, showing its threaded end *f'*, working in the interior thread, *f''*, of the packing-gland *k*. Fig. 4 is a sectional view of forcer-tube *a*, packing-glands *j* *j'*, sockets *j'* *j''*, gaskets *j''*. Fig. 5 is a detail sectional view of steam-head plug *g'* and bushing *h'*, circular groove *h''*, socket-pin *h''*, pin-hole *h'''* in said bushing. Fig. 6 is a perspective view of steam-head plug *g* and bushing *h*, showing 40 pin-hole *h''*.

My invention is described as follows: It is made in two halves, A and B, which are substantially joined together by screws or bolts and nuts *q*, and by the pipe-connections on 45 the threaded ends *r* *r'*. The steam-tube *a* is fitted into its bed loosely, so that it can be worked backward or forward by the lever *M*. The tubes *b*, *c*, *d*, and *e* have ground shoulders *b'* *c'* to fit into their ground sockets *b''* *c''*. 50 These tubes *b* *c* *d* *e* also fit a little loosely in their beds, and are allowed room for a little play between their ground shoulders and the

ground sockets *b''* *c''*, so that the injector will drain itself of water when not in use.

The steam-tube *a* and regulating-plug *f* are 55 provided with packing-glands *j* *j'* and *k*. The flanges *j''* and *k''* of these packing-glands fit into their sockets *j'* and *k'*, said sockets being first partially filled with any proper packing material. These packing-glands are provided 60 with arms having mouths which are arranged to grasp threaded studs *n* *n'*. These threaded studs are provided with nuts *n'*, which turn against the outer face of the packing-glands *j* *j'* and *k*, and press them down into their 65 sockets *j'* *k'*.

The steam-tube *a* is long and cylindrical, and reaches from the steam-chamber A' to the mixer-chamber B'. This is for the purpose of keeping the water as cool as possible up to 70 the very nozzle of the said steam-tube, and thus prevent any leakage of steam.

In a slot made between the two halves A and B the lever *M* plays. One end, *m'*, of this lever is pivoted at point *m''*, while the 75 other end plays loose in said slot. It has a hole, *m''*, in it, which loosely fits over the steam-tube *a*, and (the lever) is pivoted to the tube by screws and nuts *m''*. This lever *M* moves the steam-tube *a* back and forth; and 80 when I wish to cut off the steam from passing into it I run its rear end back into circular groove *h''* of bushing *h'*, which acts as a plug and closes the said end of said steam-tube. The check-valve *l* fits into the outer end of 85 pipe *e*, which is provided with perforations *l'* and pin *l''*.

The regulating-plug *f* is screwed into packing-gland *k*. This packing-gland has arms with mouths which fit onto and grasp studs 90 *n''*. These studs *n''* have nuts which work on them and against the outer face of the arms of said gland, and press its flange *k''* into the socket *k'*, and compress any gasket therein contained.

To start the machine, push lever *M* clear 95 back and give steam. As soon as water appears at overflows, move the said lever forward until no more water appears at overflow *p*. Then turn regulating-plug *f* forward until no more 100 water appears at overflow *o*. When the flow of the water is thus once regulated, it will not have to be moved afterward, except under change of temperature, or from the change of

the depth to the water in the cistern from which it comes, or a large change of steam-pressure, thus practically making my invention a one-lever injector.

5 The beds of the bushings h and h' have a pin, h^4 , which passes into hole h^5 of said bushings, and prevents them from turning while they are being tightened into place by screwing into them plugs $g g'$. By taking out these 10 plugs $g g'$ the whole interior of the machine is accessible by a wire in case any holes should be stopped.

This combined injector and ejector is made in two parts, so that it may be taken apart 15 by unscrewing the screws or nuts and bolts q . When so opened, the whole of the injector can be easily taken apart, as tubes a, b, c, d , and e fit loosely in their sockets, and packing-glands $j j$ and k will come out of their 20 sockets at once, and the whole thing can be taken apart at little cost or trouble and cleaned, and, if necessary, repaired.

Having described my invention, what I claim as new, and desire to secure by Letters Patent, 25 is—

1. The two halves A and B of the body of the combined injector and ejector, each having beds for the pipes a, b, c, d , and e , and for the regulating-plug f , steam-chambers A' and B', 30 sockets $j' k'$ for packing-glands j and k , beds for the plugs $g g'$ and for the bushings $h h'$, said halves A and B being firmly held together by screws or bolts and nuts q , substantially as shown and described.

35 2. The two halves A and B, having steam-chests A' B', beds for the pipes a, b, c, d , and e , the upper half, A, having overflows o and p , said halves being firmly held together by screws or bolts and nuts q , substantially as shown and 40 described.

3. In combination with halves A and B, threaded studs n , with packing-glands j , having mouths grasping said studs n , and flanges j^3 , fitting into sockets j' , with nuts n' , working 45 on threaded studs n and against the outer face of said packing-glands j , and adapted to press said flanges down into their sockets j' , substantially as shown and described.

4. In combination with the halves A and B,

threaded studs n^2 , with packing-gland k , having female screw f^2 , carrying threaded regulating-plug f , flange k^3 , fitting into socket k' , and nuts n' , working on said studs n^2 and against the outer face of said packing-gland k , and adapted to press said flange k^3 down into its 50 socket k' , substantially as shown and described.

5. In combination with halves A and B, lever M, its end m' , pivoted on pin m^2 of the lower half, B, of the body, grasping in its perforation m^4 tube a by means of nuts and bolts m^5 , and tube a , working back and forth in packing-gland j , and bushing h' , having circular groove h^2 , fitting the rear end of tube a , and serving as a plug to shut off the steam from said tube, when required, all substantially as 65 shown and described.

6. In combination with the halves A and B, pins h^4 , with bushings h and h' , fitting into their grooves, and their pin-holes h^5 , fitting on said pins h^4 , and their shoulders h^3 , fitting against 70 the shoulder of said grooves, and plugs $g g'$, screwing into said bushings, substantially as shown and described, and for the purposes set forth.

7. In combination with the combined ejector 75 and injector, having the two halves A and B, steam-chests A' and B', self-stopping overflows o and p , and ground sockets $b^2 c^2$, with tubes b, c , d , and e , having ground shoulders $b' c'$, fitting into said ground sockets $b^2 c^2$, substantially as 80 shown and described.

8. In combination with the combined ejector and injector, as above described, pipe c , having ground shoulders b' , fitting into ground shoulders b^2 , and having in its outer end perforations, l' , with check-valve l , fitting into the outer end of said pipe c , and pin l^2 , passing horizontally across the opening in the outer end of said pipe, preventing said check-valve 85 from being blown out, substantially as shown and described.

In testimony whereof I affix my signature in presence of two witnesses.

JOHN M. MARTY.
